US0D1039064S

(12) United States Design Patent (10) Patent No.: US D1,039,064 S
(45) Date of Patent: * Aug. 13, 2024

(54) TOY

(71) Applicant: Alex Hochstrasser, Zürich (CH)

(72) Inventor: Alex Hochstrasser, Zürich (CH)

() Term: 15 Years

(21) Appl. No.: 35/517,509

(22) Filed: Dec. 12, 2022

(80) Hague Agreement Data

Int. Filing Date: Dec. 12, 2022

Int. Reg. No.: DM/227205

Int. Reg. Date: Dec. 12, 2022

Int. Reg. Pub. Date: Jun. 16, 2023

(51) LOC (14) Cl. 21-01

(52) U.S. Cl.

USPC D21/519; D21/471

(58) Field of Classification Search

USPC D21/334-337, 385-386, 468-471

CPC .. A63F 9/26; A63F 9/0073; A63F 3/02; A63F 3/00697
